UNITED STATES PATENT OFFICE.

CHESTER L. HOCKNEY, OF SILVERLAKE, WISCONSIN, ASSIGNOR TO DOUGLAS DYRENFORTH,
OF CHICAGO, ILLINOIS.

WHEEL-CHAIR.

No. 909,411.

Specification of Letters Patent.

Patented Jan. 12, 1909.

Application filed November 25, 1907. Serial No. 403,800.

To all whom it may concern:

Be it known that I, CHESTER L. HOCKNEY, a citizen of the United States, residing at Silverlake, in the county of Kenosha and 5 State of Wisconsin, have invented a new and useful Improvement in Wheel-Chairs, of which the following is a specification.

My invention relates to that class of wheel-chairs in which provision is made for folding or collapsing the same when it is desired 10 to transport or store the chair, and the object of my invention is to construct a light, durable chair, which shall be rigid when distended for use, easily and readily adjusted from one position to the other, and 15 capable of being folded to a small compass in a compact manner.

Referring to the accompanying drawings: Figure 1 is a perspective view of my improved chair, the wheels being represented 20 by dotted lines; Fig. 2, a perspective view of the frame, with the wheels, back, foot and leg-rest, seat and side supports not shown; Fig. 3, a plan sectional view of the frame 25 alone, showing the same in a partially folded position; Fig. 4, a broken perspective view of the forward portion of the frame in a partially folded position; Fig. 5, an enlarged broken plan view showing one of the 30 wheel-axles, and the rule-joint adjacent thereto, and Fig. 6, a view in elevation of the parts shown in Fig. 5; Fig. 7, a broken side elevation of the adjustable foot-rest; Fig. 8, a broken plan sectional view of the 35 center pivotal rule-joint of the axle showing the locking lever, or latch; Fig. 9, a broken sectional elevation of the rule-joint shown in Fig. 8, the view being taken at the line 9 on Fig. 8 and viewed in the direction of the 40 arrow, and Fig. 10, a perspective view of the locking lever, or latch, and its engaging tongue.

In constructing my improved chair, I provide two similar non-collapsible side-frames 45 11, 11, preferably formed of tubing, each having a horizontal seat-support 12, and an arm 13, preferably parallel to the latter though spaced some distance above the same, to which its forward curved end is attached 50 in any desired manner, the arm being supplemented by a member 13^a to afford a wider support for the occupant of the chair. Each side-frame has an upward rear extension 14, terminating in a curved hook-shaped handle 55 15 and a downward forward-extension 16,

having at its end a slot 16^a (Fig. 7) flanked by lugs 17, through which passes a screw for the purpose of clamping within said extension one of two similar posts 18 to hold the same at any adjusted position. At the base 60 of each post 18 are provided ears between which is pivoted one end of a forwardly-extending arm 19, to form a hinge 20, and upon each of these arms are secured hinge-clips 21, one at its free end and one adjacent 65 to its hinge 20, and between opposite hinge-clips 21, to which their ends are pivoted forming hinges 21^a, are two members 22 extending transversely of the chair and having a platform 23, Fig. 1, secured to them 70 to form a foot-rest. This platform is divided between its ends at 23^a in line with the longitudinal center of the chair, and each member 22 is provided with a hinge 24 intermediate its ends and coincident with 75 the division 23^a of the platform. The hinges 24 are so arranged as to resist pressure from above to prevent flexing of the member 22, from a horizontal plane, but to yield to pressure from below to enable the foot-rest 80 to be folded in a manner indicated in Fig. 4, and the hinges 20 rigidly sustain the arms 19 (supporting the foot-rest) in a lowered position while permitting them to be swung 85 upwardly in folding.

A jointed axle 25 is secured in place near the forward ends of the side-frames by means of brackets 26, one of which is attached to each side-frame to extend downwardly therefrom, and at its base is rigidly 90 fastened the axle-spindle 25^b, around which the wheel revolves, to hold the same in a fixed position, relative to the frame. A hinge 27 is provided in the axle adjacent to each bracket 26, on the inside thereof, and 95 midway between these two hinges 27 and in line with the longitudinal center of the chair the axle is provided with a third or central hinge 28. A tongue 29 is attached (preferably by brazing) to the inner end of 100 one of the intermediate or central sections of the axle to project beyond the end of said section past the central hinge 28, where, at its free end, it is reinforced and provided with a slot 30, as shown in Figs. 8 and 10. The slot 30 is of such size and contour as 105 to permit the tongue 29 to surround and pass the adjacent end of the latch or locking-lever 31, which is pivoted at 32 to the other of said intermediate or central sections of the 110

axle when the latch or locking-lever is in a horizontal position, as is also indicated in Figs. 8 and 10. When the chair is being unfolded or distended to position for use 5 the tongue 29 passes the latch 31 (the latter at this time being in a horizontal position) whereupon it is swung to a vertical position causing it to overlap the projecting ends of the tongue at opposite sides of the pivot 32 10 to rigidly lock the frame chair in such position.

Near the rear of the side-frames surrounding each seat-support 12 is a clip 33 to which is pivotally attached one end of a brace or 15 transverse member 34 to form a hinge 35 adjacent to each side-frame, these hinges corresponding with the hinges 27 of the axle with which they are in longitudinal alignment. This brace 34 is provided between its 20 ends with a third or central hinge 36, in line with the longitudinal center of the chair, similar to and corresponding with the hinge 28 of the axle.

The hinges or joints employed throughout the construction of the chair-frame are 25 "rule-joints", allowing the members to swing freely in one direction but assuring rigidity to the members when in the position where the abutting shoulders of the hinges 30 are in contact. The hinges of the axle and those of the brace, or transverse member, are constructed and arranged to swing in a horizontal plane, and the pivot-pin of the central hinge 28 of the axle extends above 35 the same where it is provided with an enlarged hollow head 37, into which is suitably secured one end of a reach 38 securely held in position at a point between its ends by a depending extension 39 of the pivot- 40 pin of the central hinge 36 of the brace 34. The rearward extension of the reach is provided with a substantially vertical tubular bearing 40, for the purpose of receiving and swiveling the shank or spindle of a fork 41, 45 carrying a wheel 42, said fork and wheel being shown by dotted lines in Fig. 1.

A seat 43 provided at the front and rear with transverse members 44 is secured in position by clips 45, which loosely surround 50 the seat-supports 12, of the two side-frames, and are attached to the adjacent ends of the transverse members 44. The seat and transverse members 44 are divided centrally at 55 in line with the longitudinal center of the chair similarly to the foot-rest, as before explained, and hinges 46^a are provided on the under side of the members 44 coincident with the division 46 therein to act in the same manner as the hinges 24 of the foot- 60 rest.

A flexible or yielding back 47 is provided, preferably of leather or canvas, and is suitably attached to the upward rear extensions of the two side-frames, and a leg support 48, similar to the back 47, is attached in like

manner to the downward forward extensions 16 of the frame-members, while between the seat-support 12 and arm 13 of each of the side-frames is secured a side 49, preferably of the same material as the back and leg-support, suitably fastened in place. As shown in the drawings, these sides are hung over the arms 13 with their lower edges extending to within a short distance of the seat-support 12 to which they are laced for the purpose of holding them in place, thus affording an air-space between the sides and seat, but this however is not essential and may be dispensed with.

The operation of the chair is as follows: 80 Suppose the chair to be in position for use, as shown in Fig. 1, the latch 31 is swung on its pivot from a vertical position to that of a horizontal, when the tongue 29 is free to be forced past the latch 31, the contour of the 85 slot conforming to that of the adjacent end of the latch and in registration therewith in this position, as before explained. The joints of the foot-rest and seat are then broken, that is, raised so that their central 90 hinges are above a "dead center", then drawing forward the reach 38 thereof causes the axle 25 and brace 34 to swing upon their respective hinge-joints to draw the side-frames inwardly from opposite sides toward 95 the longitudinal center of the chair, and this movement may be completed or supplemented by pressure exerted upon the side-frames from opposite sides. The action of drawing forward the reach serves also to draw the 100 rear wheel into the space between the two forward wheels, thereby materially shortening the longitudinal length of wheel-base when in its collapsed condition. It will be 105 observed that the back and leg-support are formed of flexible material which naturally folds during the operation of collapsing the chair. By having the leg-support relatively low with relation to the chair-body as shown, ready access is afforded to the latch for locking and unlocking the chair: but it is to be 110 understood that the invention is in no sense limited to this or similar details in the matter of material or dimensions. As the chair is thus being folded the two sections of the 115 seat and foot-rest are folded together, the clips connecting the two divisions of the seat with the frame acting as hinges.

The foot-rest may, if desired, be turned 120 upwardly upon the hinges 20, until the arms 19 rest against the extensions 16 of the side-frames in a manner suggested in Fig. 4 to thereby compact the parts when in the folded position.

While the chair has been described and is 125 illustrated in the drawings as employing three wheels, two of which are large and provided with hand-rails by which the user may propel himself, while the frame is shown as provided with the handles at the 130

upper extremity, it will readily be understood that the handles referred to may be wholly omitted or that the hand-rails may be wholly omitted on the wheels, or that instead of one rear wheel two rear wheels may be used having a common supporting axle or frame, these various modifications in this type of chair being already well known in the art. It will also be understood that while the parallel side-frames are shown and described as made preferably of tubular material the invention is in no sense limited to the material in this regard, since the frames may be of wood or soft metal, as is also the case with the axle or brace. It will also be understood that modifications to suit the taste of the maker or user are possible in the general design of the chair either as a whole or as to its details without departing from my invention.

What I claim as new and desire to secure by Letters Patent is—

1. In a wheel-chair of the type adapted to be collapsed transversely, the combination with substantially parallel side-frames each carrying a rigidly-attached axle-spindle for a side wheel, of front and rear connecting bars each having an intermediate folding-joint and a folding-joint toward each end, said bars constructed and arranged to fold in the same direction, a central rigid reach connecting said bars and a wheel held by said central reach at a point to cause the wheel-base to be shortened upon folding, as set forth.

2. In a wheel-chair of the type adapted to be collapsed transversely, the combination with substantially parallel side-frames each carrying a rigidly-attached axle-spindle for a side wheel, of front and rear connecting-bars each having an intermediate folding-joint and a folding-joint toward each end, said bars constructed and arranged to fold in the same direction, a central rigid reach connecting the intermediate joints of said connecting-bars, and a wheel pivotally held by said central reach at a point to cause the wheel-base to be shortened by the act of folding, as set forth.

3. In a wheel-chair of the type adapted to be collapsed transversely, the combination with substantially parallel side-frames each carrying a rigidly-attached axle-spindle for a side wheel, of front and rear connecting-bars each having an intermediate folding-joint and a folding-joint toward each end, said bars constructed and arranged to fold in the same direction, a central rigid reach connecting the intermediate joints of said connecting-bars, a wheel held by said central reach at a point to cause the wheel-base to be shortened upon folding, and a locking device on one of the connecting-bars locking the same at its intermediate joint and there-

by preserving the frame rigidly in its dis- 65 tended position, as set forth.

4. In a wheel-chair of the type adapted to be collapsed transversely, the combination with substantially parallel side-frames each carrying a rigidly-attached axle-spindle for 70 a side wheel, of front and rear connecting bars each having an intermediate folding-joint and a folding-joint toward each end, a central rigid reach connecting the intermediate joints of said connecting-bars, a wheel 75 carried by said central reach, a tongue rigid with a section of one of said connecting-bars, its free end overlapping the adjacent section of the connecting-bar and provided at its free end with a slot, and a latch pivoted to 80 the other section of said connecting-bar and adapted to engage the tongue at its slot to rigidly lock the frame in a distended position.

5. In a wheel-chair of the type adapted to be collapsed transversely, the combination 85 with substantially parallel non-collapsible side-frames each carrying a rigidly-attached axle-spindle for a side wheel, of front and rear connecting-bars each having an intermediate 90 "rule-joint", and a similar joint in each of said connecting-bars adjacent to each side-frame, said joints arranged to afford rigidity to the frame when in a distended position, a central rigid reach connecting the intermediate joints of the connecting-bars, a wheel carried by the reach, a tongue rigid with a section of one of said connecting-bars, its free end overlapping the adjacent section of the connecting-bar 95 and provided at its free end with a slot, and a latch pivoted to said adjacent section and adapted to engage the tongue at its slotted end to lock the frame in its distended position, substantially as set forth.

6. In a wheel-chair of the type adapted to be collapsed transversely, in combination substantially parallel side-frames each having rigidly secured thereto a wheel-carrying axle-spindle, front and rear connecting-bars each having lateral and intermediate joints 105 as described, said bars constructed and arranged to fold in the same direction, a reach connecting the intermediate joints of said connecting-bars, a wheel carried by said reach at a point to cause the wheel-base to be 110 shortened upon folding, and a longitudinally-divided jointed seat supported laterally on the frame-members, as described, whereby on collapsing, the sides of the chair fold toward each other, and when the parts 115 are all distended they are held against collapsing, substantially as set forth.

7. In a wheel-chair of the type adapted to be collapsed transversely, the combination with substantially parallel side-frames each carrying a rigidly-attached axle-spindle for 125 a side wheel, of front and rear connecting bars each having an intermediate folding-

joint and a folding-joint toward each end, said bars constructed and arranged to fold in the same direction, a central rigid reach connecting the intermediate joints of said connecting bars, a wheel carried by said central reach at a point to cause the wheel-base to be shortened upon folding, and an adjustable foot-rest carried by the side-frames and provided with hinges to permit the foot-rest 10 to be folded against said side-frames, the foot-rest being longitudinally divided and jointed to permit the foot-rest to fold as the chair is collapsed, substantially as set forth.

8. In a wheel-chair of the type adapted to be collapsed transversely, the combination with substantially parallel non-collapsible side-frames each carrying a rigidly-attached axle-spindle for a side-wheel, of front and rear connecting-bars each having an intermediate folding-joint and a folding-joint toward each end, said bars constructed and arranged to fold in the same direction, a central rigid reach connecting the intermediate joints of said connecting-bars, a wheel carried by said central reach at a point to cause the wheel-base to be shortened upon folding, a jointed seat supported laterally on said side-frames, and an adjustable foot-rest carried by the side-frames, said seat and foot-rest being divided longitudinally of the chair to permit them to fold as the chair is collapsed, substantially as described.

9. In a wheel-chair of the type adapted to be collapsed transversely, the combination with substantially parallel side-frames each carrying a rigidly-attached axle-spindle for a side wheel, of front and rear connecting-bars each having an intermediate folding-joint and a folding-joint toward each end,

a central rigid reach connecting the intermediate joints of said connecting-bars, a wheel carried by said reach, a post telescoping with the forward extension of each side-frame and adjustable thereon, each of said posts carrying a forwardly-projecting arm hinged to the post, a longitudinally-divided foot-rest hinged at opposite sides to said arms, and a lock for rigidly holding the frame in a distended position, substantially as described.

10. A collapsible rolling-chair comprising in combination substantially rigid side members each comprising a seat-portion, an arm-portion and a back-portion, a rigidly-attached axle-spindle on each side-member and a wheel thereon, front and rear frame-connections each having lateral joints and a central joint, said frame-connections constructed and arranged to fold in the same direction, a central rigid reach extending longitudinally of the chair and connected to the central joints of said frame-connections, a pivoted wheel secured to said reach at a point to cause the wheel-base to be shortened upon folding, a longitudinally-divided jointed seat hinged to the side frames, a longitudinally divided foot-rest hinged to the side-frames, and means for locking the frames in distended position, the parts being arranged substantially as described whereby the collapsing of the chair or the distention thereof may be performed without removing any of the parts.

CHESTER L. HOCKNEY.

In presence of—

B. A. BECKER,
F. J. LINGENFELDER.
